(57) **CLAIM**

The ornamental design for an earwash device, as shown and described.

DESCRIPTION

FIG. 1 is a perspective view of an earwash device showing my new design.
FIG. 2 is a front view thereof.
FIG. 3 is a rear view thereof.
FIG. 4 is a left side view thereof.
FIG. 5 is a right side view thereof.
FIG. 6 is a top view thereof.
FIG. 7 is a bottom view thereof.
FIG. 8 is a rear, right, bottom perspective view thereof.
FIG. 9 is an enlarged detail view of area 9 shown in FIG. 2.
FIG. 10 is an enlarged detail view of area 10 shown in FIG. 6.
FIG. 11 is an enlarged detail view of area 11 shown in FIG. 7; and,
FIG. 12 is an enlarged detail view of area 12 shown in FIG. 8.

The dash-dash broken lines in the figure drawings illustrate portions of the earwash device that form no part of the claimed design.
The dash-dot-dash broken lines in the figure drawings represent a boundary of the enlargement views and form no part of the claimed design.

1 Claim, 12 Drawing Sheets
